MILK BOTTLE LOCK

Pedro M. Otero, San Juan, Puerto Rico

Application June 11, 1934, Serial No. 730,441

4 Claims. (Cl. 232—41)

This invention relates to a milk bottle holder, the general object of the invention being to provide means whereby one or more bottles can be held by the device and another bottle by the closure member of the device, the present invention being an improvement on that forming the subject matter of a patent granted to me on May 8, 1934, No. 1,957,610.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:—

Figure 1 is an elevation of the device, showing the same attached to a wall or other support.

Figure 2 is a horizontal section through the lock on line 2—2 of Figure 3.

Figure 3 is a vertical section on line 3—3 in Figure 2.

In these views, the letter A indicates a casing which has a flange 1 on its rear side which is adapted to be bolted to a wall B or the like by the bolts 2. The casing is open at its lower end and the side walls at their lower edges are curved inwardly, as at 3, to provide retaining flanges for the mouths of bottles placed therein. One end of the casing is open and this end is adapted to be closed by a closure C which is hingedly connected to a part of the casing, as shown at 4, so that it can be swung in a horizontal plane, as shown in full and dotted lines in Figure 2. A recess 5 is formed in the front part of the casing and the front side of the closure member is formed with an extension 6 which fits in the recess when the closure is in closed position. This closure is of substantially semicircular shape and is formed with the lower inwardly extending flange 7 for engaging part of a bottle mouth and at the front, an inwardly curved projection 8 is provided on the closure which forms an extension of the curved part of the closure and a continuation of the flange 7 thereof and a similar extension 9 is formed at the open end of the casing and curves inwardly from the rear wall of the open end of the casing. Thus when the closure is in closed position and a bottle has its mouth placed in the closure, said bottle cannot be moved from the closure into the casing as the extensions

8 and 9 will prevent the bottle from being moved from the closure into the casing.

A keeper recess 10 is formed in the front part of the closure for receiving the locking bolt 11 slidably arranged in a tubular part 12 of the casing and which extends across the open end of the casing at the top thereof. A rod 13 is connected with the bolt and passes through the tubular part 12, which is formed with a rear extension 12' for passing through the wall B and 10' the free end of said rod is provided with a handle 14 so that a person within a building, a part of which is shown at B, can open the lock to permit the closure to be swung to open position while remaining inside of the building. The milkman 15 can also open the closure by passing his finger or a tool up through the open lower part of the closure to press a pin 15 on the bolt projecting through a slot 16 in the tubular part 12, so as to retract the bolt. However, when a bottle is in 20 the closure, the pin 15 cannot be reached, so that after the milkman places a bottle in the closure and swings the closure to closed position, a person on the outside of the building cannot open the device.

In order to protect the locking parts and also to hide them from view of a mischievously inclined person, I provide a hinged cover 17 of angle shape in cross section which is pivoted to the top part of the closure, as at 18, with a spring 19 normally holding the cover against the front of the tubular member 12 so as to cover the slot 16 and the pin 15.

Thus it will be seen that the milkman can open the closure and place bottles in the casing and one in the closure and then he can swing the closure shut and it will be locked in closed position. The housekeeper, by pulling upon the rod 13, can unlock the device so that the bottles can be removed therefrom. When one bottle of milk is 40 to be delivered, then this bottle can be placed in the closure and if desired, a similar closure can be placed at the other end of the device and this is desirable where two families are living in the same house.

The lock is normally held closed by a spring 20 and if the device is not placed on a door so that the householder can hold the bolt retracted while swinging the closure to open position, any suitable means may be provided for holding the bolt retracted while one goes to a point where he can swing the closure to open position. Usually when the bolt is retracted, the weight of the bottle will promptly open the closure member so that its keeper cannot be again engaged by the bolt but 55

the closure member will not open sufficiently to permit the bottle to drop therefrom.

It is thought from the foregoing description that the advantages and novel features of the invention will be readily apparent.

It is to be understood that changes may be made in the construction and in the combination and arrangement of the several parts, provided that such changes fall within the scope of the appended claims.

What is claimed is:—

1. In a holder of the class described, a casing having one end open and its bottom open, means at the bottom of the casing for engaging the neck of a bottle, a substantially semi-circular closure for the open end of the casing hingedly connected with the casing and having a bottle retaining flange at its lower part, said lower part being open, a bolt carried by the open end of the casing, said closure having a keeper for the bolt, a pin connected with the bolt and projecting into the closure whereby one can move the bolt to releasing position from the lower part of the closure, exterior means for retracting the bolt, and a spring actuated cover member in the upper part of the closure for covering the pin.

2. A milk bottle holder comprising a casing having one end open and with its bottom open, the side walls of the casing having inwardly extending parts at their lower edges for forming bottle retaining flanges, a substantially semi-circular closure member hingedly connected with the rear part of the casing adjacent its open end, said closure member having its bottom open with a lower retaining flange thereon, the front part of the casing having a recess therein adjacent its open end and the closure having an extension thereon for fitting in the recess, an inwardly curved extension in the closure having a flange forming a continuation of the closure flange, a tubular member extending across the open end of the casing, a bolt slidably arranged in the tubular member and the front part of the closure member having a keeper recess therein for receiving the bolt, a rod connected with the bolt and passing through the tubular part, said tubular part having a slot therein, and a pin carried by the bolt and projecting through the slot.

3. A milk bottle holder comprising a casing having one end open and with its bottom open, the side walls of the casing having inwardly extending parts at their lower edges for forming bottle retaining flanges, a substantially semi-circular closure member hingedly connected with the rear part of the casing adjacent its open end, said closure member having its bottom open with a lower retaining flange thereon, the front part of the casing having a recess therein adjacent its open end and the closure having an extension thereon for fitting in the recess, an inwardly curved extension in the closure having a flange forming a continuation of the closure flange, a tubular member extending across the open end of the casing, a bolt slidably arranged in the tubular member and the front part of the closure member having a keeper recess therein for receiving the bolt, a rod connected with the bolt and passing through the tubular part, said tubular part having a slot therein, a pin carried by the bolt and projecting through the slot, and a spring actuated closure member in the upper part of the first mentioned closure member for covering the pin and slot.

4. A milk bottle holder comprising a casing having one end open and with its bottom open, the side walls of the casing having inwardly extending parts at their lower edges for forming bottle retaining flanges, a substantially semi-circular closure member hingedly connected with the rear part of the casing adjacent its open end, said closure member having its bottom open with a lower retaining flange thereon, an inwardly curved extension in the front of the closure having a flange forming a continuation of the closure flange, an inwardly curved extension in the rear part of the casing adjacent the open end and provided with a flange which forms a continuation of the closure flange, a tubular member extending across the open end of the casing, a bolt slidably arranged in the tubular member and the front part of the closure member having a keeper recess therein for receiving the bolt, and a member connected with the bolt and passing through the tubular part for retracting the bolt.

PEDRO M. OTERO.
